DESIGN FOR MIRROR ATTACHMENT FOR SUN VISOR

Glen A. Johnson, Connersville, Ind.

Application August 3, 1934, Serial No. 52,800

Term of patent 7 years

To all whom it may concern:

Be it known that Glen A. Johnson, a citizen of the United States, residing at #2735 Grand Ave., Connersville, in the county of Fayette and State of Indiana, has invented a new, original, and ornamental Design for a Mirror Attachment for Sun Visor, of which the following is a specification, reference being had therein to the accompanying drawing, forming a part thereof, in which—

Fig. 1 is a plan view showing my new design.

Fig. 2 is a perspective view of my new design showing its application to a sun visor.

The drawing is shaded to represent a reflective surface.

I claim:

The ornamental design for mirror attachment for sun visor as shown and described.

In testimony whereof, I affix my signature.

GLEN A. JOHNSON.
